US00D538984S

(12) **United States Design Patent** (10) **Patent No.:** **US D538,984 S**
King (45) **Date of Patent:** **** Mar. 20, 2007**

(54) **DRYING DEVICE FOR USE IN DETAILED MOTORCYCLES**

(76) Inventor: **Vincent M. King**, 142 Springdale Dr., Leesburg, GA (US) 31763

(**) Term: **14 Years**

(21) Appl. No.: **29/206,572**

(22) Filed: **Jun. 1, 2004**

(51) **LOC (8) Cl. 15-05**

(52) **U.S. Cl. D32/15**

(58) **Field of Classification Search** D32/1, D32/15, 16, 17, 21, 18, 25; 15/344, 345, 15/405; D23/213

See application file for complete search history.
